VIBRATORY ALIGNER

Howard S. Orth, Clair R. Oberst, and William E. Cramer, Columbus, Ohio, assignors to Industrial Ceramic Products Inc., Columbus, Ohio, a corporation of Ohio

Application November 26, 1937, Serial No. 176,679

3 Claims. (Cl. 209—97)

This invention relates to vibratory transfer apparatus and has particular reference to an improved vibratory table by which materials are advanced longitudinally of the table and while undergoing such advancement are automatically arranged in a predetermined or desired order.

In a companion application, executed of even date herewith, we have set forth and claimed a method of handling sagger pins of the type employed in the firing of ceramic ware in kilns, wherein such pins, withdrawn from a disorderly mass, are aligned and grouped so that they may be stacked in orderly rows in shipping cartons or containers. The present invention has to do particularly with the construction of a vibratory table used in said process for effecting the longitudinal alignment and parallel order of sagger pins following manufacture thereof and preparatory to their packaging.

It is an object of the present invention to provide apparatus of an improved automatic type by which the sagger pins deposited in an unorganized manner on the apparatus may be automatically handled so that said pins, upon discharge from the apparatus, will be disposed in longitudinally aligned parallel order and adapted for packaging operations.

For a further understanding of the invention, reference is to be had to the following description and the accompanying drawing, wherein:

Fig. 1 is a view partly in side elevation and partly in vertical section of the vibratory table comprising the present invention;

Fig. 2 is a vertical transverse sectional view taken through the table on the plane indicated by the line II—II of Fig. 1 and disclosing more particularly the upstanding ribs and side walls of the table which provide the longitudinally extending pin arranged ways;

Fig. 3 is a transverse sectional view taken through the pin receiver at the discharge end of the table, the plane of the figure being indicated by the line III—III of Fig. 1;

Fig. 4 is a top plan view of the table, disclosing its operation of effecting longitudinal position in parallel order of sagger pins deposited at random thereon;

Fig. 5 is a perspective view of a sagger pin.

Referring more particularly to the drawing, the numeral 1 designates the improved vibratory conveying and assorting machine comprising the present invention. The machine consists of a table 2 which is so supported that it may be vibrated by a high frequency to move materials deposited on the table longitudinally thereof.

The supporting and vibrating mechanism for the table is a well known construction, and consists, in this instance, of a plurality of flat, parallel, leaf springs 3. These springs are secured at their lower ends, as at 4, to a suitable stationary base 5, while the upper ends of said springs are clamped or otherwise firmly secured, as at 6, to lugs or enlargements 7 formed with the under side of the table 2. Mounted on the base 5 is a motor cradle 8 which effects the support of an electric vibrating motor 9. This motor is energized, preferably by the use of alternating current, in an intermittent manner in order to attract a table mounted armature 10 toward the pole or poles of the motor. When the motor is momentarily deenergized, the table returns to its normal position under the return flexing of the springs 3. Inasmuch as this construction does not form a claimed part of the present invention, a further detailed description thereof will be accordingly omitted.

The present invention is particularly directed to the construction of the table 2. In this instance, the table is formed from metal and comprises a substantially flat bottom 12, vertically upstanding, parallel, longitudinally extending side walls 13—13, an end wall 14 at the material receiving end of the table, and an open discharge end. To render the table adaptable for the purpose of effecting a desired positioning of sagger pins deposited thereon, the said table is further provided with a plurality of parallel, longitudinally extending, relatively spaced and upstanding ribs 15 which, in connection with the side walls 13—13 and the bottom 12, produce a plurality of parallel, longitudinally extending, pin-advancing ways 16. These ribs, contiguous to the discharge end of the table, are provided with upstanding lugs or shoulders 17, the latter being arranged in staggered or offset relationship, as shown in Figs. 1 and 4, in order to deflect sagger pins moving transversely on the upper edges of said ribs so that the pins will be deposited in the ways 16 in a desired manner.

In the use of the apparatus, sagger pins, of the type indicated at 18, are deposited on the receiving end of the table in a disorderly random manner. Such a group of pins is indicated by the reference character B. By the operation of the motor 9, and consequent vibration of the table 2 at high frequencies, the pins are moved longitudinally along the table from the receiving end of the latter to its discharge end. The construction of the ways 16 serves in greater part to cause alignment of the pins so that they all ex-

tend longitudinally of the ways 16 by settling into said ways. Sometimes, however, the pins become transversely positioned on the upper edges of the ribs, as indicated by the pin D in Fig. 4. When 5 this occurs, the shoulders 17, by reason of their formation and relative positions, engage such a transverse pin and swing it around so that it will drop longitudinally into one of the ways 16. By 10 this construction and operation, the sagger pins 15 discharged from the table will all extend in the same direction and in parallel order with respect to each other.

Sagger pins are formed from heat treated ceramic materials and, as shown in Fig. 5, are substantially triangular in cross sectional configuration. This is done so that the pins will present knife edges in effecting the support of ceramic ware positioned thereon, the knife edges being desired in order to minimize the area of contact 20 between the pins and the ware supported thereby. The pins vary in length, that is to say, the same are made in different sizes, depending upon the uses to which the pins are to be placed, but in manufacturing operations pins of but one size 25 are advanced along the table for any given run. In this manner, the machine may be readily adapted to sagger pins of different size or lengths.

Secured to the discharge end of the table 2 is a receiver 19. The latter in this instance, comprises a cup-like member into which the pins discharged from the table 2 are deposited so that the pins extend in parallel order transversely of the receiver. Preferably, the receiver is provided with a curved or arcuate bottom 20, with a stationary vertical end wall 21 and an adjustable opposing end wall 22. The wall 22 is adjustable in order that it may be adapted to sagger pins of different lengths, although, if desired, the receiver 19 may be detachably carried in connection with the end of the conveyor table and of such size as to be adapted for the reception of pins of fixed or given length. It will be noted that the wall 21 is spaced from the discharge edge of the table 2 in order to provide a slot or 40 gap 23. This spacing is such that in the event of breakage of the pins or pins of undesirable short length, such broken pins, or short length pins, will not bridge the gap between the table and the receiver, but will fall through the slot 45 23 and will thus be automatically rejected from the machine.

In the receiver 19, groups of longitudinally aligned parallel pins are constantly being formed when the machine is in operation. These groups

may be manually removed by the machine attendant with the pins of each group in a fixed or desired order. Groups of pins so removed may then be stacked in orderly rows and piles in shipping containers, such as paper board cartons 5 for storage or transportation. The machine operates economically and efficiently in securing the desired alignment of the relatively peculiarly shaped sagger pins so that improved ways of packaging such pins may be used, rather than 10 the mere shipping of the pins in loose bulk form, without reference to position or order, in barrels or other similar containers.

What is claimed is:

1. Apparatus for handling sagger pins of a predetermined length comprising a table formed with a plurality of longitudinally extending pin-positioning ways, a pin receiver carried by the discharge end of said table, said receiver being spaced from said table to provide a material rejecting gap extending transversely of the apparatus and having a width less and a length greater than the length of the pins to be handled, and means for supporting and vibrating said table and receiver. 15 20 25

2. Apparatus for handling sagger pins of a predetermined length comprising a table, a plurality of longitudinally extending upstanding ribs provided on said table, said ribs being spaced a distance less than the length of the pins to be handled, a receiver provided at the discharge end of said table, the bottom wall and the ribs of said table terminating in spaced relation from the receiver to provide a pin rejecting gap extending substantially across the entire width of the table, 30 the width of said gap being less than the length of pins to be handled, and means for supporting and vibrating said table. 35

3. Apparatus for handling sagger pins of a predetermined length comprising a table formed with a plurality of longitudinally extending pin-positioning ways, a pin receiver carried by the discharge end of said table, adjustable wall means provided with said receiver for varying the size thereof to adapt the receiver to pins of different 40 sizes, said receiver being spaced from said table to provide a material rejecting gap extending transversely of the apparatus and having a width less and a length greater than the length of the pins to be handled, and means for supporting and 45 50 vibrating said table and receiver.
